(57) **CLAIM**

I claim the ornamental design for a perineometer, as shown and described.

DESCRIPTION

FIG. 1 is an isometric view of the perineometer in accordance with my new design;

FIG. 2 is an isometric view of the perineometer of FIG. 1;

FIG. 3 is a side elevation view of the perineometer of FIG. 1,

the opposite side being a mirror image thereof;

FIG. 4 is a top plan view of the perineometer of FIG. 1;

FIG. 5 is a bottom plan view of the perineometer of FIG. 1; and,

FIG. 6 is a front elevation view of the perineometer of FIG. 1.
